UNITED STATES PATENT OFFICE.

FREDERICK JOHN SHANISEY, SR., OF ROCHESTER, NEW YORK, ASSIGNOR TO FITZ-EMPIRE DOUBLE PIVOT LAST COMPANY, OF AUBURN, MAINE, A CORPORATION OF MAINE.

LAST.

Application filed February 7, 1918. Serial No. 215,782.

To all whom it may concern:

Be it known that I, FREDERICK J. SHANISEY, Sr., a citizen of the United States, residing at Rochester, in the county of Monroe and State of New York, have invented certain Improvements in Lasts, of which the following description, in connection with the accompanying drawings, is a specification, like reference characters on the drawings indicating like parts in the several figures.

This invention relates to collapsible lasts, and in particular to lasts having a separate heel block arranged to move relative 15 to the forepart about a fixed or moving center, and which are commonly called hinge-lasts. Collapsible lasts of one common type offer a resilient resistance to movement from either extended or collapsed 20 position. Collapsible lasts of another type offer such resistance only to movement from extended position and tend to return to extended position when "broken" or collapsed. It is an important object of my invention 25 to provide a last which, without sacrifice of other important advantages, will have the characteristic advantages of both of these types and which is transformable from one type to the other, and important 30 features of the invention consist in such an organization.

Heretofore great difficulty has been experienced with collapsible lasts in securing the requisite strength in connection with 35 cheapness of construction and rapid shortening action.

Accordingly, it is a further object of my invention to provide a hinge last which shall have the above-discussed and other 40 advantages while avoiding the disadvantages of heretofore known hinge-lasts.

To this end a feature of the invention consists in a two-part last having a substantially horizontal joint surface preferably 45 located in the vertically central portion of the last to enable the last to resist the stresses imparted by the leveling machine, and provided with a pin and slot hinge connection such as to enable the last to be 50 shortened easily and rapidly.

These and other features of the invention, comprising certain arrangements and combinations of parts will be understood from the following description of a preferred embodiment of the invention, se-

lected for purposes of illustration and shown in the drawings in which,

Figs. 1 and 2 are views of the last extended and collapsed, respectively; and

Figs. 3 and 4 are similar views of a different form of the last showing the plates in reversed position for the sake of clearness.

The last shown is of the two-part form having a forepart 10 and a heel part 12. A part of the cone of the last is removed as at 14, to permit collapsing as will be well understood. The joint surface on the forepart comprises a substantially horizontal portion 16, located about midway of the vertical dimension of the last, and a portion 18 extending downwardly and backwardly to the tread surface of the last. The heel part has two corresponding surfaces 20, 22, cut to fit the surfaces 16, 18, respectively, the surfaces 16, 20 forming abutting shoulders when the last is extended.

The two last parts are joined by a plate 24, firmly anchored preferably in the heel part by rivets 26, and having two slots 28, 30, arranged at a large angle with each other. Two pins 32, 34 in the forepart engage in the slots. The last being in extended position, the left end of the slot 30 is closer to the pin 34 than the right end.

As the heel part swings up and the pin 34 moves to the right in the slot 30, the pin 32 will drop toward the bottom of the slot 28. This gives the plate 24 and the heel part carried by it a rotary movement about

a continually moving center, or in other words, movement of combined translation and rotation, lifting the heel part and turning and drawing it forward to collapse the last. A very rapid and efficient shortening action is produced, as indicated in the dotted lines in Figs. 2 and 4, which show several successive positions of the heel part.

The relation between the cuts 16—20 and 18—22 and the bonding mechanism is an important one, and should not be overlooked. The construction whereby the relative movements of the fore and heel parts are prescribed, as described, has a special advantage in a last the secant cuts or faces of which provide positive abutting shoulders intermediate the ends of said cuts, such as the shoulders formed at 16—20 in the drawing. It is advisable that the horizontal cut 110

16—20 be located well up in the last in order to secure the requisite strength, particularly against the twisting stresses of the leveling operation. When the heel part of a 5 hinge last of heretofore known construction swings about a fixed center, the center is preferably placed high in the last for the sake of strength, and the shortening action is very slow (and in some lasts is even 10 negative) at its beginning. If the fixed center were to be located low in the last, the additional disadvantage would be incurred of having to slope the cut 18—22 so far to the rear, in order to permit the 15 surface 22 to clear the high corner 35, that either the heel plate must be shortened or else the whole joint moved forward in the last. For practical reasons, neither procedure is feasible. In the last of the present 20 invention, the raising of the plate 24 by the co-action of the slots 28, 30 on the pins, enables the upper portion of the surface 22 to clear the corner 35 without undue sloping of the cut 18—22, and at the same time the 25 heel part is carried forward rapidly from the beginning of the collapsing movement, the slot 28 being inclined to the vertical in the forward direction, so that every movement of every portion of the heel part has 30 a substantial forward component.

Since the plate 24 is rigidly connected to the heel part, any movements of said plate relatively to the forepart are necessarily transmitted to the heel part. The movements hereinbefore described, desirable in 35 order to clear the corner 35 without undue sloping of the faces 18—22, are obtained by the two guides provided respectively by the co-action of slot 30 with pin 34 and the co- 40 action of slot 28 with pin 32. The lower guide 28—32 is nearly vertical and the upper guide 30—34 is directly above it and is at such angle relatively thereto that at the very start of relative movements of the fore 45 and heel parts from extended toward collapsed positions the distance between the lower rivet 26 and the pin 34 begins to lessen and the last begins to shorten, and at the same time the slot 28 begins to move up 50 along pin 32 caused by the upper slot 30 riding along pin 34. This causes the entire plate 24 to begin to rise, thus lifting the heel part amply to clear the corner 35 as described. These movements continue until 55 the last is collapsed.

Means for locking or holding the last parts in relative position is provided, comprising a plate 36, pivotally mounted on the lower pin 26 and lying beside and in contact with 60 the plate 24. It carries near its forward end a projection 38, sloping off into two cam-shaped depressions 40, 42, one on each side. A roller 44 is mounted on the pin 34 and forms a bearing co-operating with the 65 projection 38. The roller seats in one or

other of the depressions when the heel part is in either extreme position.

The plate 36 is resiliently held in contact with the roller 44 by a spring 46. The spring 46, the diameter of which is less than 70 the combined thickness of the plates 24 and 36, is mounted in two overlapping holes 48, 50 in the plates 24 and 36, respectively. The hole in the plate 36 is lower than the hole in the plate 24, so that a spring 46 placed 75 in the holes will rest against the plate 36 with its upper end and the plate 24 with its lower end. This will always hold the plate 36 pressed firmly against the roller 44 in either position of the heel part. It is 80 to be noted that no additional boring and consequent weakening of the last is necessary in order to insert this spring, which is not thicker than the two plates combined.

The forepart of the last may be bored at 85 52 to receive a spring 54 arranged to engage a projection 56 on the plate 36, or a projection 58 on the plate 24. One plate is shown without its projection on each sheet of the drawings for the sake of clearness in illustration. In the former case the spring 46 may be dispensed with, if desired, (and is accordingly not shown on Figs. 3, 4) and in either case, since the line of action of the spring 54 lies above the pin 32, the spring 90 54 will force the last back into extended position from collapsed position, without attention on the part of the operator, and irrespective of the tendency of the locking member 36 to hold the last in collapsed position. 100

I have thus provided a last which can be made resiliently self-extending or can be made to oppose movement from either extended or collapsed position by the simple 105 expedient of inserting or removing the spring 54.

Having thus described my invention, what I claim as new and desire to secure by Letters Patent of the United States is:—

1. In a collapsible last, a hinge mechanism constructed and arranged to offer substantial resistance to initial movement from collapsed position, and means acting automatically to return the last parts from 115 collapsed to extended position, said means being removable when desired to permit the free action of the elements offering resistance to movement of the last parts.

2. In a collapsible last, a hinge mechanism constructed and arranged to offer resilient resistance to movement from collapsed to extended position and means constructed and arranged to supply the force necessary to overcome the resistance to 125 movement from collapsed position, said means being removable when desired to permit the free action of the elements offering resistance to movement of the last parts.

3. A collapsible last having hinge mech- 130

anism, means for holding the last in extended position and for holding it in fully collapsed position, and means operating to inhibit the latter function of the holding means.

4. A collapsible last comprising hinge mechanisms constructed and arranged resiliently to resist movement from either extended or collapsed position, and means for causing the last, nevertheless, to return automatically to extended position when collapsed, said means being removable when desired, whereby the said normal operation of the hinge mechanism is secured.

15 5. In a two-part last, a hinge plate rigidly mounted in one last part, and having a slot, a pin mounted in the other last part and engaging in the slot, the pin and slot being constructed and arranged to guide the 20 heel part in a combined rotational and translational movement to collapse the last, and a second plate pivotally mounted in the former last part, arranged to engage the pin resiliently and to tend to hold the last 25 in one of its two positions, and a removable means for automatically returning the last from collapsed to extended position.

6. In a two-part collapsible last, a hinge connection constructed and arranged to 30 swing the heel part on the forepart by a combined movement of translation and rotation, to shorten the last, an abutment mounted in one last part and a member pivotally mounted in the other last part and 35 constructed and arranged to engage the abutment and to tend to hold the last in one of its two positions, and means for automatically returning the last from collapsed to extended position.

40 7. In a hinge-last, a forepart having a joint surface comprising a substantially horizontal portion and a portion extending downwardly and rearwardly at an angle thereto approximately half the thickness of 45 the last to the tread face, the heel part having a correspondingly arranged surface and a horizontal overhanging surface arranged to fit the said surfaces on the forepart, and a hinge plate fastened rigidly in the heel

50 part and having two slots, and pins in the forepart engaging in the slots, the slots being constructed and arranged in such manner as to cause the plate to rise and turn forward simultaneously about the pins to 55 collapse the last, and the downwardly extending joint surfaces being constructed and arranged so that the heel part surface will clear the corner between the two said forepart surfaces as the last collapses.

8. In a two-part last, a hinge plate rigidly mounted in one of the last parts and having a slot, a pin in the other last part engaging in said slot, the slot and pin being constructed and arranged to permit the heel part to rotate and slide forward, in combination with a holding member pivotally mounted in the heel part of the last and having a portion constructed and arranged to engage the pin to hold the last in collapsed or extended position.

9. In a two-part collapsible last, a hinge connection constructed and arranged to permit swinging of the heel part on the forepart by a combined movement of translation and rotation, to shorten the last, an 70 abutment mounted in one last part independent of the hinge connection and a member pivotally mounted in the other last part and constructed and arranged to engage the abutment and resiliently hold the last in 80 collapsed or extended position.

10. A hinge last having a slot in each part, a hinge plate and a holding plate mounted side by side in the slots, the plates having slightly non-registering apertures and 85 a spring in the apertures bearing against opposing sides in the two apertures for controlling the holding member.

11. A convertible hinge last comprising a hinge mechanism having a member constructed and arranged to tend to hold the last resiliently in extended or collapsed position, and a removable member normally acting to overcome the tendency of the said first-named member to hold the last in collapsed 95 position.

12. A convertible hinge last having a forepart, a heel part, a hinge mechanism uniting said parts, an abutment on one last part, and a member on the other last part 100 arranged resiliently to engage the abutment in two positions to tend to hold the last in collapsed and extended positions, respectively, and a spring, operating to move the last automatically from collapsed to 105 extended position, said spring being removable to permit normal action of the remaining last parts.

13. A convertible hinge last having a hinge mechanism constructed and arranged 110 in itself to extend the last automatically from collapsed position, including a member removable therefrom at will, thereby leaving a mechanism acting to hold the last resiliently in collapsed position.

In testimony whereof I have signed my name to this specification.

FREDERICK JOHN SHANISEY, Sr.
